US00D964555S

(12) **United States Design Patent** (10) **Patent No.:** **US D964,555 S**
(45) **Date of Patent:** **** Sep. 20, 2022**

(54) **ABSORBENT ARTICLE**

(71) Applicant: **PRODUCTOS FAMILIA S.A.**,
Medellín (CO)

(72) Inventor: **Fabio Alberto López Pimienta**,
Medellín (CO)

(73) Assignee: **PRODUCTOS FAMILIA S.A.**,
Medellín (CO)

(**) Term: **15 Years**

(21) Appl. No.: **29/756,952**

(22) Filed: **Nov. 2, 2020**

(51) LOC (13) Cl. **24-04**

(52) U.S. Cl.

USPC **D24/125**
